US0D1006863S

(12) **United States Design Patent** (10) **Patent No.:** **US D1,006,863 S**
(45) **Date of Patent:** **** Dec. 5, 2023**

(54) **STABILIZED CAMERA DEVICE**

(71) Applicant: **ARASHI VISION INC.**, Shenzhen
(CN)

(72) Inventors: **Limin Ma**, Guangdong (CN); **Jingkang Liu**, Guangdong (CN); **Fei Gao**, Guangdong (CN)

(73) Assignee: **ARASHI VISION INC.**, Shenzhen
(CN)

(**) Term: **15 Years**

(21) Appl. No.: **35/515,459**

(22) Filed: **Oct. 12, 2022**

(80) **Hague Agreement Data**

Int. Filing Date: **Oct. 12, 2022**
Int. Reg. No.: **DM/224336**
Int. Reg. Date: **Oct. 12, 2022**
Int. Reg. Pub. Date: **Oct. 28, 2022**

(57) **CLAIM**

The ornamental design for a stabilized camera device, as shown and described.

DESCRIPTION

1. Stabilized camera device

1.1 : Front

1.2 : Back

1.3 : Left

1.4 : Right

1.5 : Top

1.6 : Bottom

1.7 : Perspective

1.1-1.7 are drawings showing an embodiment of the stabilized camera device; the present product is used as a stabilized camera device to be fixed on a display device or placed on a desktop for implementing photographing, thus acquiring image data of the surrounding environment, and also can be used for character tracking and recognition. The broken lines form no part of the claimed design.

1 Claim, 7 Drawing Sheets
